UNITED STATES PATENT OFFICE.

JOHN T. HAWKINS, OF TAUNTON, MASSACHUSETTS.

PIPE-WRENCH.

SPECIFICATION forming part of Letters Patent No. 404,619, dated June 4, 1889.

Application filed December 7, 1888. Serial No. 292,886. (No model.)

To all whom it may concern:

Be it known that I, JOHN T. HAWKINS, of Taunton, in the county of Bristol and State of Massachusetts, have invented a new and useful Improvement in Pipe-Wrenches, which invention or improvement is fully set forth and illustrated in the following specification and accompanying drawings.

The object of this invention is to provide in the well-known solid "alligator" pipe-wrench an adjustable stop or tooth partially embedded in or lying upon the smooth jaw in such a way that the lateral strain brought upon said stop shall be transferred upon the jaw itself and said adjustable stop or tooth be supported by said jaw and applied to assist in the rotation of a pipe at the farthest point possible from the point of contact of the serrated jaw with the pipe.

20 The invention will first be described in detail, and then particularly set forth in the claim.

The instrument now well known as the solid "alligator wrench" consists of two jaws so constructed as to form a V-shaped opening between them, one of the jaws being toothed or serrated and the opposite one plain. In the operation of such a wrench upon a pipe or rod, the latter slides upon the smooth jaw 25 until the teeth or serrations on the opposite jaw take firm hold on the said pipe or rod. The tendency is found to be, however, in such construction, to more or less crush a pipe operated on, under considerable rotative strain, by the forcing of the pipe still farther up into the V-shaped opening. It has been proposed 30 to obviate this tendency by providing an adjustable screw-stop passing through the vertex of the angle made by the inner surfaces of the two jaws. This latter construction is, however, open to the objection that the stop is applied so near to the point of contact of the serrated jaw with the pipe as to interfere with a firm hold being taken upon the pipe by said 35 serrations or teeth, and if the wrench rotates upon the pipe after contact of the screw-stop, it operates to bring considerable transverse strain upon said stop, and particularly when operating upon pipes of large diameter, at 40 which time the screw-stop is protruded far-

thest into the angle of the jaws. In this construction, also, the said stop cannot be made to perform the function of a tooth or teeth without insuring transverse bending of the stop. My invention, however, provides an adjustable stop lying in a recess formed in the smooth jaw or lying upon and supported by the smooth jaw, so that said jaw may operate upon the pipe at the farthest point possible from the point of contact of the serrated jaw therewith merely as a stop, or be formed into a sharp tooth upon that side, and thus to provide against crushing by obstructing the further entrance of the pipe into the angle of the jaws after the serrated jaw has taken firm hold, 55 and also to assist in rotating the pipe by acting as an abutment or stop or as a tooth, as may be preferred.

In the accompanying drawings, Figure 1 illustrates in side view my invention applied to such a wrench; and Fig. 2 shows a transverse view of the wrench, partly in section, on the center line of the adjustable stop-screw. Fig. 3 shows a side view of the jaw end of the wrench, with the point of the stop-screw 75 pointed to serve merely as a stop without any action as an opposite tooth.

In said figures, the number 1 indicates the body of the wrench; 2, the serrated jaw; 3, the plain jaw, and 4 the stop-screw, threaded 80 in its enlargement 5, formed upon the wrench for purposes of strength. In Fig. 1 the point of the stop-screw 4 is made square on the end, so as to form a sharp corner to penetrate the pipe and act as a nearly-opposite tooth. 85 In Fig. 3 this point is tapered, so as to act merely as a sudden increase of angle of the jaws, to prevent further entrance of the pipe, which latter is shown as a dotted circle in Figs. 1 and 3.

I do not claim, broadly, an adjustable stop; but

As of my invention I claim—

In combination with a pipe-wrench constructed of a serrated or toothed jaw, as 2, and an opposite smooth or unserrated jaw, as 3, forming an acute angle with each other, an adjustable stop or tooth, as 4, supported upon or within a recess formed in the smooth jaw and adjustable practically in line with said 100

smooth jaw, whereby said stop or tooth may be adjusted for any given diameter of pipe or rod within the range of said wrench's embrace, so as to allow the entrance of the pipe or rod into the angle formed by the jaws, by sliding upon said smooth jaw until the serrated jaw has taken firm hold upon said pipe or rod, and then preventing any further en-

trance of and resulting tendency to crush said pipe, to assist as a nearly oppositely applied stop or tooth in rotating said pipe, substantially as set forth.

JOHN T. HAWKINS.
